United States Patent Office.

SILAS SLOAT, OF MORGAN, OHIO.

Letters Patent No. 70,035, dated October 22, 1867.

IMPROVEMENT IN HORSE-SHOES.

The Schedule referred to in these Letters Patent and making part of the same.

TO ALL WHOM IT MAY CONCERN:

Be it known that I, SILAS SLOAT, of Morgan, in the county of Ashtabula, and State of Ohio, have invented a new and improved Horse-Shoe; and I do hereby declare that the following is a full, clear, and exact description thereof, which will enable others skilled in the art to make and use the same; reference being had to the accompanying drawings, forming part of this specification.

This invention relates to a new and improved horse-shoe, and it consists in constructing the same with a view to its ready attachment to and detachment from the hoof, and to accomplish this end without the employment of nails.

The object of the invention is to obtain a means whereby any person of ordinary ability may apply a shoe to the hoof of a horse, and detach it therefrom, without the aid of a shoer or smith, and also obtain a shoe which may be applied to a diseased or defective hoof without injuring the same. In the accompanying sheet of drawings—

Figure 1 is a side view of my invention, applied to the hoof of a horse.

Figure 2, a front view of the same.

Figure 3, a plan or top view of the same.

Figure 4, a vertical section of the same, taken in the line *xx*, fig. 3.

Figure 5, an inverted plan of the shoe.

Figure 6, a transverse section of the same, taken in the line *yy*, fig. 5.

Similar letters of reference indicate like parts.

A represents the horse-shoe, which is made substantially the same as those in common use, and provided with toe and heel-calks *abb*. This shoe is fitted within a flange, B, which is of T-form in its transverse section, the shoe being secured to the under side of the horizontal portion *e* of the flange by screws *d*, as shown clearly in figs. 5 and 6. The lower edge of the upright portion *e* of the flange is flush with the under surface of the shoe, and to the inner side of this portion *e*, above *a*, there are secured, by rivets *f* or otherwise, two pieces of leather C C, the front ends of which are connected at the front of the hoof by a leather strap or thong, *g*, passing through metallic loops D D, secured to the leather pieces C C. These pieces of leather C C extend entirely around the wall of the hoof, and to the upper part of each piece C of leather there is attached an elastic metal strip or bar, E, the front ends of the latter being secured to the leather by rivets *g*. These strips or bars E extend to the rear edges of the leather pieces C, and have each an eye, *h*, at the rear end, through which a strap, F, passes, and each strip or bar has a lateral projection or spur, *i*, and these projections or spurs pass through the leather pieces C C into the wall of the hoof, and are kept therein by the strap F. To the rear part of each piece C there is attached a metal bar, *j*, having a lip, *k*. These lips extend over the upper edges of E to keep the rear parts of C C upward in proper position. By this simple means the shoe is firmly secured to the hoof without the aid of nails, and the shoe may be readily applied and detached. When the shoe becomes worn it may, without any difficulty whatever, be readily unscrewed from the flange B and repaired, or replaced by a new one. The invention also admits of a shoe being applied to a defective hoof, which will not admit of having a shoe nailed to it, and the horse used without any injury or risk.

Having thus described my invention, I claim as new, and desire to secure by Letters Patent—

The securing the horse-shoe A to a metal flange, B, having a vertical portion, *e*, with a horizontal portion, *e*, projecting from its inner side or surface, in combination with the pieces C of leather or other suitable material attached to the portion *e* of the flange, as shown, and the elastic metal strips or bars E attached to C C, and provided with lateral projections or spurs *i*, which pass through C C into the wall of the hoof, and are retained therein by the strap F, all arranged substantially as and for the purpose set forth.

SILAS SLOAT,
